UNITED STATES PATENT OFFICE.

FREDERICK L. ALLEY, OF SYDNEY, NEW SOUTH WALES, AUSTRALIA, ASSIGNOR TO
UNITED SHOE MACHINERY COMPANY, OF PATERSON, NEW JERSEY, A CORPOR-
ATION OF NEW JERSEY.

INSEAM-SHOE-SEWING MACHINE.

1,157,200.

Specification of Letters Patent.

Patented Oct. 19, 1915.

Application filed January 13, 1913. Serial No. 741,776.

To all whom it may concern:

Be it known that I, FREDERICK L. ALLEY, a citizen of the United States, residing at Sydney, New South Wales, Australia, have 5 invented certain new and useful Improvements in Inseam-Shoe-Sewing Machines; and I do hereby declare the following to be a full, clear, and exact description of the invention, such as will enable others skilled 10 in the art to which it appertains to make and use the same.

This invention relates to sewing machines, and more particularly to sewing machines for sewing inseams of boots and shoes.

15 In machines of this class as ordinarily constructed the work is fed by a lateral movement of the feed point which engages the insole in the channel during the sewing operation. The feed point penetrates only 20 a slight distance into the substance of the insole, and bears substantially the entire strain of feeding the shoe. The back rest which assists in supporting the shoe in the proper position with relation to the stitch 25 forming devices is yieldingly held against the upper during the feeding movement of the shoe, and it is necessary for the feed point to feed the shoe against the friction or drag of the back gage on the upper.

30 The primary object of the present invention is to produce an inseam shoe sewing machine having a back rest, the work engaging face of which is advanced in the direction of feed with the shoe as the shoe is fed, 35 and which is operated so that there is no objectionable rubbing contact between the shoe and the back rest at any time during the sewing operation.

With the above objects in view, the invention 40 comprises certain novel and improved features hereinafter described and particularly pointed out in the claims, the advantages of which will be apparent to those skilled in the art.

45 The invention will be readily understood from an inspection of the accompanying drawings illustrating the preferred embodiment of the invention and the following detailed description thereof.

50 In the drawings, Figure 1 is a front elevation of an inseam shoe sewing machine embodying the invention; Fig. 2 is a view

in side elevation of the machine, partly broken away and partly in section, looking from the right; Fig. 3 is a view in side elevation of the machine, partly broken away and partly in section, looking from the left; Fig. 4 is a detail plan view partly in section illustrating the back rest, the back rest slide, and a portion of the mechanism 55 for actuating the back rest; Fig. 5 is a detail view of the back rest and certain associated parts, looking in the direction of the axis of the back rest; Fig. 6 is a view in rear elevation of the parts shown in Fig. 5, taken 60 in a plane parallel with the axis of the back rest; Fig. 7 is a view in front elevation of the parts illustrated in Fig. 5, taken in a plane parallel with the axis of the back rest; and Fig. 8 is a sectional view taken on the 65 line 8—8 of Fig. 6.

The machine illustrated in the drawings has the same general construction and arrangement of parts as the inseam shoe sewing machine shown and described in the 75 patent to French and Meyer, No. 412,704, dated October 8, 1889. The particular construction and arrangement of the parts of the machine, with the exception of the back rest and the mechanism for actuating the 80 back rest, are substantially the same as illustrated and described in the application of Alley and Beckman, Serial No. 600,574, filed January 3, 1911.

In the drawings, 1 indicates the curved 85 hook needle, 2 the looper, 3 the awl or feed point, 4 the channel guide, 5 the thread finger, and 6 the welt guide supported on the forward end of the welt guide slide 7. The construction and arrangement of the above 90 mentioned parts of the machine, and the mechanism for operating the same, are substantially the same as of the corresponding parts of the machine illustrated and described in the Alley and Beckman application 95 referred to above.

In the illustrated embodiment of the invention, the back rest indicated at 8 consists of a roll rotatably mounted on a stud 9 secured in an arm 10 projecting laterally from the forward end of the work rest slide 11. The work rest slide is pressed forward to yieldingly engage the work rest with the shoe by a spiral spring 12 connected at one 100

extremity to a fixed stud 13 and at the other to a ratchet disk 14 rotatably mounted on the stud. A pinion is carried by the ratchet disk and meshes with a rack formed on the 5 back rest slide. During a part of the stitch forming operation, the back rest slide is locked by a pawl 15 carried by a lever 16 and arranged to engage the teeth of the ratchet disk 14. The lever 16 is actuated to 10 engage the pawl 15 with the teeth of the ratchet disk by a tension spring 17. The lever 16 is operated to release the pawl 15 from the ratchet disk and unlock the back gage by the engagement of a cam actuated 15 lever 18 with a pin 19 on the lever 16. The construction and operation of the mechanism above briefly described for actuating and locking the back rest slide is substantially the same as that disclosed in the above 20 mentioned patent to French and Meyer.

In order to obviate any friction or drag which might be exerted by the back rest tending to hold back the shoe while it is being fed and to assist in feeding the shoe, a 25 rotary movement is given to the back rest about the stud 9 in a direction to advance the work engaging portion thereof with the shoe as the shoe is fed. During the period in a cycle of operations of the machine when 30 the shoe is stationary, the back rest is held from rotation so that there may be no rubbing contact between the back rest and the shoe which might injure the leather. A step by step rotary movement is therefore imparted to the back rest, the periods of rotation occurring while the shoe is being fed and the periods of rest when the needle is advancing through the work and retracting to draw the new loop through the materials 40 and the preceding loop.

The mechanism for imparting the step by step movement to the back rest is shown particularly in Figs. 5, 6, 7 and 8. This mechanism comprises a ratchet disk 20 secured to or formed integral with the roll 8 and a pair of pawls 21 and 22 pivotally mounted on an oscillatory plate 23 arranged to engage the teeth on the ratchet disk 20, being pressed into engagement with the 50 ratchet disk by springs 24. The acting end of the pawl 21 is arranged half a tooth in advance of the pawl 22, as shown in Fig. 5. The plate 23 upon which the pawls are supported is rotatably mounted on the stud 9 below the ratchet disk 20, and is oscillated on the stud to impart a step by step rotary movement to the roll back rest 8. The roll is held from backward rotation as the plate 55 is moved to retract the pawls along the circumference of the ratchet disk by a ball clutch. The ball 42 of the clutch operates in a slot in the plate 23, and is arranged to engage the lower face of the disk 20 and an inclined surface 43 formed on the arm 10. 60 A coiled spring 44 interposed between the

ball and a lug 45 on the arm 10 tends to wedge the ball between the inclined surface 43 and the lower face of the disk 20. The movement of the ball is limited by a stop 46.

The mechanism for oscillating the plate 70 23 comprises a link 25 pivotally connected at one end to the plate 23 and at the other to the arm 26 of a bell crank lever 26-27 fulcrumed on a stud 28 mounted on the back rest slide. The arm 27 of the bell 75 crank lever carries a roll 29 which engages in a groove 30 in the under side of a block 31 secured to the end of a slide 32 which is arranged to reciprocate in a guide 33 at right angles to the direction of movement 80 of the back rest slide. The bell crank lever 26-27 and the block 31 operate in a slot in the back rest slide, as shown in Figs. 3 and 4. By means of the construction above described, the reciprocatory movement of the 85 slide 32 causes the oscillation of the bell crank lever 26-27, and through the connection of said lever with the plate 23, the said plate is oscillated on the stud 9 to actuate the back rest roll. As the back rest slide 90 moves forwardly or rearwardly, the roll 29 slides in the groove in the block 31, and the movements imparted to the bell crank lever 26-27, and thereby to the back rest roll by 95 the reciprocatory movement of the slide 32, are not affected by the position of the back rest slide.

The mechanism for reciprocating the slide 32 consists of a link 34 connected at one end by a pin 35 with the slide, and at the other by a bolt 36 with the lever 37 fulcrumed at 100 38 on the frame of the machine, and carrying a cam roll at 39 engaging a cam path 40 formed in a cam disk secured to the cam shaft of the machine. The cam path 40 is 105 arranged in timed relation to the other parts of the machine so that the back rest roll 8 is rotated to advance the work engaging portion thereof with the shoe as the shoe is fed by the lateral movement of the awl or feed point. The actuating mechanism for the back rest is constructed and arranged to advance the work engaging portion of the back rest a distance equal to the length of one stitch during each actuation thereof. 110

In order that the rotary movement of the back rest may be varied to correspond with variations in the feed for varying lengths of stitch, the lever 37 is formed with a slot 41 through which the bolt 36 passes, and the movement imparted to the back rest for each oscillation of the lever 37 can be varied by adjusting the bolt 36 in the slot 31. 115

By actuating the back rest to assist in feeding the shoe, the drag of the back rest against the shoe during the feeding of the shoe is eliminated, and the feed point is relieved of a large part of the strain of feeding the shoe. It is also to be noted that 125 there is no objectionable rubbing engage- 130

ment between the back rest and the shoe at any time during the stitch forming operation.

What is claimed is:—

- 5 1. An inseam shoe sewing machine, having, in combination, stitch forming devices including a curved hook needle, a back rest support, a back rest to bear against the upper at the side of the last and below the bottom of the last when the shoe is in sewing position movably mounted on the support, and means for moving the back rest on its support always in a direction to advance the work engaging portion thereof.
- 10 2. An inseam shoe sewing machine, having, in combination, stitch forming devices, a back rest slide, a rotary back rest mounted on the back rest slide to engage the shoe and means for rotating the back rest always 20 in the same direction.
- 15 3. An inseam shoe sewing machine, having, in combination, stitch forming devices including a curved hook needle, a back rest support, a rotary back rest to bear against the upper at the side of the last and below the bottom of the last when the shoe is in sewing position mounted on the back rest support, and means for rotating the back rest always in a direction to advance the 30 work engaging portion thereof.
- 35 4. An inseam shoe sewing machine, having, in combination, stitch forming devices including a curved hook needle, a back rest support, a back rest to bear against the upper at the side of the last and below the bottom of the last when the shoe is in sewing position movably mounted on the support, and means for moving the back rest on the support always in a direction to advance the 40 work engaging portion thereof in timed relation to the operation of the stitch forming devices.
- 45 5. An inseam shoe sewing machine, having, in combination, stitch forming devices including a curved hook needle, a movable back rest to bear against the upper at the side of the last and below the bottom of the last when the shoe is in sewing position constructed to provide an endless surface for 50 engagement with the shoe, and means to actuate the back rest to advance the shoe engaging portion thereof.
6. An inseam shoe sewing machine, having, in combination, stitch forming devices including a curved hook needle, a rotary back rest to bear against the upper at the side of the last and below the bottom of the last when the shoe is in sewing position, and means to rotate the back rest always in the same direction.
- 10 7. An inseam shoe sewing machine, having, in combination, stitch forming devices, feeding means, a back rest support, a back rest movably mounted on the support, and means for actuating the back rest on its support always in a direction to advance the work engaging portion thereof and in timed relation to the operation of the feeding means.
- 15 8. An inseam shoe sewing machine, having, in combination, stitch forming devices, a back rest slide, a back rest movably mounted on the slide, means to lock and unlock the slide, means for yieldingly engaging the back rest with the shoe during the feeding of the shoe, and means for actuating the back rest to advance the work engaging portion thereof step by step in timed relation to the operation of the stitch forming devices.
- 20 9. An inseam shoe sewing machine, having, in combination, stitch forming devices including a curved hook needle, a back rest support, a back rest to bear against the upper at the side of the last and below the bottom of the last when the shoe is in sewing position movably mounted on the support, means for actuating the back rest to advance the work engaging portion thereof step by step in timed relation to the operation of the stitch forming devices.
- 25 10. An inseam shoe sewing machine, having, in combination, stitch forming devices, feeding means, a back rest slide, a rotary roll mounted on the forward end of the slide to engage the shoe, a ratchet and pawl mechanism for rotating said roll to assist in feeding the shoe, and a clutch to prevent retrograde movement of the roll.
